UNITED STATES PATENT OFFICE

162,343

STOCKING

Isador Rabinovitz, Philadelphia, Pa.

Application May 17, 1949, Serial No. 2,713

Term of patent 3½ years

(Cl. D47—7)

To all whom it may concern:

Be it known that I, Isador Rabinovitz, a citizen of the United States and a resident of Philadelphia, county of Philadelphia, State of Pennsylvania, have invented a new, original, and ornamental Design for a Stocking, of which the following is a specification, reference being had to the accompanying drawings, forming a part hereof, wherein:

Figure 1 is a fragmentary rear perspective view of a stocking showing my new design, the same design being duplicated on opposite sides of the stocking seam; and

I claim:

The ornamental design for a stocking, as shown.

ISADOR RABINOVITZ.
